UNITED STATES PATENT OFFICE.

GEORGE M. DIEHL, OF PERU, INDIANA.

MARKING-MACHINE.

No. 907,577.

Specification of Letters Patent. Patented Dec. 22, 1908.

Application filed September 24, 1908. Serial No. 454,656.

To all whom it may concern:

Be it known that I, GEORGE M. DIEHL, a citizen of the United States, residing at Peru, in the county of Miami and State of Indiana, have invented certain new and useful Improvements in Marking-Machines, of which the following is a specification.

The object of my invention is to produce a machine capable of producing upon successive articles an individualizing mark the character of which may be readily maintained or changed as desired, the apparatus being particularly designed for use in laundries to properly mark and individualize the property of different customers. It is of course to be understood however that the machine is not at all limited to such use.

The accompanying drawings illustrate an embodiment of my invention, Figure 1 being a side elevation; Fig. 2 a vertical section; Fig. 3 a front elevation with some of the parts broken away; Fig. 4 an axial section through the main drive shaft; Fig. 5 a plan of some of the parts shown in Fig. 4; Fig. 6 a detail showing the character of movement of the inking pad; Fig. 7 a side elevation, on a larger scale, of the forward ends of the carrying arms for the removable type wheels; Fig. 8 a side elevation of the removable type wheels; Fig. 9 a detail of the operating end of one of the setting arms.

In the drawings, 20 indicates a suitable frame upon each side of which are pivoted, at 21 and 22 respectively, swinging arms 23 and 24 the forward ends of which are connected in pairs by links 25. The upper end of each link 25 is forwardly extended beyond the forward end of arm 23 and provided with a notch 26, and each link 25 is provided, near its lower end and on its inner face, with an inwardly projecting pin 27 adapted to receive the notched end 28 of an arm 29. Secured to the middles of the two arms 29 are the ends of a pin 30 which form an axis for a plurality of type wheels 31 provided upon their peripheries with a multiplicity of marking members 32. Each arm 29 is provided with a clamping screw 33 adapted to enter the corresponding notch 26 and clamp arms 29 and 25 together. Pivoted at 34 to the outer ends of arms 29, is a U-shaped detent 35 the cross bar 36 of which is adapted to be drawn into engagement with the marking elements 31, between any two portions 32 thereof, by suitable light springs 40. The

upper end of one arm of detent 35 is beveled at 37 so as to engage a roller or pin 38 so that the cross bar 36 will be withdrawn from the members 31 when the parts are in the normal position shown in Figs. 1 and 2.

Journaled in the frame 20 upon pin 50 is a plurality of gear wheels 39, one for each element 31. Journaled upon the cross pin 41 is a plurality of setting segments 42 one for each one of gears 39 each of said segments having a range of movement sufficient to produce nearly a complete rotation of its corresponding marking member 31. For convenience in setting the setting segments 42 I provide each one of said segments with a setting arm 43 said arms being projected through between bars 44 provided upon their under edges with ratchet teeth 45 adapted to be engaged by a detent 46 carried by the adjacent arm 43. Lying adjacent each lever 43 is an arc-shaped plate 47 upon which appears a series of characters corresponding in character and relative position to the characters carried by that marking wheel 31 corresponding to the adjacent operating arm. Arranged adjacent the notched bars 44 are releasing bars 48 adapted to be brought into engagement with the detents 46 so as to withdraw them from the teeth 45 and permit the return of the segments 42 to normal position by their respective springs 49. Any suitable mounting may be used for the operating bars 48. In the drawings I show each of said bars provided at its ends with inclined slots 43', 48' through which stationary pins 51 51 pass. The several bars 48 are connected by links 52 with a lever 53 which, in turn, is connected to a push pin 54 by means of which it may be operated. In order to prevent accidental displacement of gears 39 I provide a cross bar 55 adapted to lie between any two teeth of the several gears 39 and this cross bar is carried by levers 56 controlled by a push pin 57.

Journaled in suitable bearings on the main frame 20 is a main drive shaft 61 having secured thereto a pair of cams 63 63 each of which receives, and operates upon, a pin or roller 64 carried by the rear end of the adjacent arm 24, the rear end of each arm 23 being provided with counterweights 65 to balance wheels 31. Mounted upon one end of shaft 61 adjacent, and outside of, one of the cams 63, is a friction clutch member 66 con-

nected to the cam 63 by screws or pins 66 in such way as to prevent relative rotation but permit relative axial movement. Light springs 67 are provided to normally urge the 5 clutch member outwardly and slidably mounted in shaft 61 is a shifting bar 68 engaging at its outer end a collar 69 which lies outside of the clutch member 65 and controls its axial movement. The inner end of bar 68 10 is extended through shaft 61 to a point between the frame members 20 and there provided with a radially extending finger 71 adapted to be engaged by a stop finger 72 and thereby withdrawn inwardly against the 15 action of spring 73 and the springs 67.

Finger 72 is pivoted at 74 on the main frame and is connected to an arm 75 which extends downwardly and is connected to a link 76 which, at its forward end, is connected 20 to a rocking anvil 77 provided at its upper end with a work-receiving portion 78 cushioned on the rocking anvil by means of a spring 79. In order to lock the anvil in working position I provide a detent 81 25 adapted to drop into a notch 82 formed in link 76 and detent 81 is provided with an upwardly extending arm 83 arranged in the plane of a cam 84 secured to shaft 61.

In the form of machine shown I have 30 shown marking instruments intended to apply an indelible or other ink to the material to be marked and therefore, in order to supply the marking instrument with a supply of ink and in order to keep the 35 marking members or type free from lint I provide the following mechanism. Pivoted at 85 on the main frame is a pair of levers 86 the lower ends of which carry a brush 87 adapted to be swung into engagement with 40 the type 32 when the same are lowered to a proper position. The upper ends of levers 86 are connected to links 88 which links are connected to levers 89 connected to links 91 provided at their lower ends with rollers 92 45 adapted to be engaged by cams 93 carried by shaft 61. Also pivoted to the main frame is a pair of levers 100 the upper ends of which are connected by links 101 with levers 102 (which may be conveniently mounted 50 upon the same pivot as the pivot of levers 89) and these levers 102 are connected to links 103 provided at their lower ends with rollers 104 adapted to engage cams 105 carried by shaft 61. The links 91 and 103 are controlled in their movement by links 107 and 108 respectively. Pivoted to and between the lower ends of links 100, at 110, is an inking pad 111 adapted, when the parts are in normal position, to lie in engagement with a 55 supply pad 112 the inner end of which lies within a reservoir 113 readily supplied through a tube 114. Secured to the pad 111 is an arm 115 carrying a pin 116 lying within a slot 117 formed in the lower end of a lever 60 118 pivoted at 119 on the main frame.

Levers 100 and 118 are normally drawn to the position shown in Fig. 1 by light springs 121 and 122, respectively.

In order to drive the machine, any suitable clutch coöperating with the clutch member 65 may be provided. I have found a convenient form to be a cup-shaped clutch member 131 coaxial with the clutch member 65 and carried by the shaft 132 of a suitable motor 133. 70

Flanking the work-receiving portion 78 of the swinging anvil are suitable handle members 135. A spring 136 is attached to link 76 and is adapted to normally hold the swinging anvil 77, and the stop finger 72, in 80 the position shown in full lines in Fig. 2.

A spring 137 is attached to detent 81 so as to urge it toward the position shown in dotted lines in Fig. 2. In the form shown, this spring 136 is also connected to arm 75 85 and therefore must be somewhat lighter than the spring 136.

The operation is as follows:—Starting with the parts in the positions shown in full lines in Figs. 1 and 2, the operator pushes push pin 90 57 inwardly and holds the same in that position in one hand while, with the other, arms 43 are moved in order to shift segments 42 so as to bring the desired portions 32 of any number of the inking members 31 to marking 95 position, this being indicated by the position of the several arms 43 relative to the indicators 47, and the segments 42 being held in place by the detents 46. With the number of parts shown in the drawings the number of combinations of characters is very great indeed and when the desired combination has been set pin 57 will be released, whereupon bar 55 will drop between two teeth of each one of the gears 39 and thus 100 prevent any further movement thereof. Thereupon the operator will place the article to be marked upon the anvil portion 78 and will swing the anvil to the position indicated in dotted lines in Fig. 2, thus drawing finger 110 72 up away from the projected portion 71 of bar 68. This movement permits detent 81 to drop into notch 82 so as to hold the anvil in recording position and permits springs 73 and 67 to urge the friction clutch member 65 115 into engagement with the coöperating clutch. Thereupon a rotation of shaft 61 is had in the direction indicated by the arrow. The first movement withdraws the inclined upper end 37 of detent 35 from roller 38 and thus permits the detent 35 to drop between the adjacent two teeth of each of the marking members 31 and thus hold the same against any possibility of misplacement. Continued rotation of shaft 61 brings cams 105 into engagement with their respective rollers 104 and, through links 103, levers 102, links 101 and levers 100, swing the inking pad 111 forward 120 into engagement with the marking members 31, said marking members, moving down- 130

ward in the meantime and the inking pad being turned upwardly by the action of levers 118, arms 115, pins 116 and slots 117. The inking pad is quickly withdrawn, as cams 105 5 pass rollers 104, and the marking members are continued in their downward movement by cams 63 such cams being so shaped as to carry the marking members down with sufficient speed to cause them to strike the anvil 10 and to compress spring 79 and thus impress the ink upon the goods placed upon the portion 78. Continued movement of shaft 61 causes a retraction of the marking members toward normal position and, as they move 15 upwardly cams 93 are brought under rollers 92 so as to swing the brush 87 (through links 91, lever 89, link 88, levers 86) into engagement with the recently used portion of the marking members and free them from lint. 20 The brush 87 is quickly returned to its normal position and the marking members 31 brought into mesh with their respective gears 39. Sometime before the resumption of normal position of the marking members, cam 25 84 is brought into engagement with arm 83 of detent 81 so as to withdraw it from notch 82 and permit the anvil to resume its normal position, this movement at the same time bringing finger 72 down into the path of 30 movement of the projection 71 of bar 68 so that said finger 72 serves to draw bar 68 inwardly and withdraw the clutch member 65 from the driving clutch member 131. If a considerable number of articles are to be 35 marked with the same distinguishing mark the operator continues to place the articles in succession upon the anvil portion 78 and return the same to the position indicated by dotted lines in Fig. 2, whereupon the operation 40 will be repeated, no change in the marking instruments taking place during these successive operations. If a change in setting of the marking instruments is desired the operator pushes push pin 54 so as to bring 45 the releasing segment 48 into engagement with the several detents 46 thus withdrawing them from the ratchet teeth 45 and permitting springs 49 to cause the segments 42 to resume their normal positions thus operating, 50 through the respective gears 39, upon the several marking members 31 to return them to normal or zero position. If a second marking action upon the piece is desired it is merely necessary for the operator to hold the 55 anvil in the receiving position at the time when detent 81 is being withdrawn.

It will be noticed that, by releasing the clamping screws 33, the marking members 31 may be readily and quickly withdrawn and 60 replaced so that, if desired, a plurality of structures such as is shown in Fig. 8 may be provided each with a characteristic type, thus greatly increasing the range of the machine.

65 I claim as my invention:—

1. In a machine of the class described, the combination of a marking member having a plurality of marking portions, a work holder, means for setting the said marking member to bring a selected portion thereof in position 70 to coöperate with the work holder, means for moving the marking member toward the work holder and out of connection with the setting means, and means for locking the marking member against misplacement while 75 out of engagement with the setting means.

2. In a machine of the class described, a marking member comprising a plurality of wheels each carrying a plurality of marking portions, a plurality of setting arms one for 80 each marking member, intermediate connections between each of said setting arms and its marking member, indicating means coöoperating with the setting arms for indicating the positions of the marking members, a work holder, means for throwing the marking member toward the work holder and out of engagement with the setting means, and means for locking the marking members in selected position. 85

3. In a machine of the class described, the combination of a plurality of marking members each carrying a plurality of marking portions, a carrier upon which said marking members are mounted, a work holder arranged in the path of movement of the marking members, a plurality of setting members, intermediate connections between each of said setting members and one of the marking members separable upon movement of the marking members toward the work holder, a lock for locking the marking members in set position, and means for automatically withdrawing said lock when the marking members are in setting position. 95

4. In a machine of the class described, the combination of a plurality of marking members each carrying a plurality of marking portions, a carrier upon which said marking members are mounted, means for detachably securing said marking members as a unit to said carrier, a work holder arranged in the path of movement of the marking members, a plurality of setting members, intermediate connections between each of 110 said setting members and one of the marking members separable upon movement of the marking members toward the work holder, a lock for locking the marking members in set position, and means for automatically withdrawing said lock when the marking members are in setting position. 115

5. In a machine of the class described, the combination of a marking member comprising a plurality of rotatable wheels each 120 having a plurality of marking portions, setting means adapted to mesh with said wheels, said setting means comprising a plurality of adjustable segments each geared to one of the marking wheels, means for setting 130

said segments and indicating the positions thereof, a work holder, and means controlled by the work holder for separating the marking wheels from the setting means and driving the marking member toward the work holder.

6. In a machine of the class described, the combination of a marking member comprising a plurality of rotatable wheels each having a plurality of marking portions, setting means adapted to mesh with said wheels, said setting means comprising a plurality of adjustable segments each geared to one of the marking wheels, means for setting said segments and indicating the positions thereof, a work holder, means controlled by the work holder for separating the marking wheels from the setting means and driving the marking member toward the work holder, a brush, and means for automatically intermittently driving said brush into engagement with portions of the marking wheels.

7. In a machine of the class described, the combination of a marking member comprising a plurality of rotatable wheels each having a plurality of marking portions, setting means adapted to mesh with said wheels, said setting means comprising a plurality of adjustable segments each geared to one of the marking wheels, means for setting said segments and indicating the positions thereof, a work holder, means controlled by the work holder for separating the marking

wheels from the setting means and driving 35 the marking member toward the work holder, an inking pad, an ink font, and means for automatically intermittently driving the inking pad from the font to the marking wheels and return.

8. In a machine of the class described, the combination of a marking member comprising a plurality of rotatable wheels each having a plurality of marking portions, setting means adapted to mesh with said 45 wheels, said setting means comprising a plurality of adjustable segments each geared to one of the marking wheels, means for setting said segments and indicating the positions thereof, a work holder, means controlled by the work holder for separating the marking wheels from the setting means and driving the marking member toward the work holder, a brush, means for automatically intermittently driving said brush 50 into engagement with portions of the marking wheels, an inking pad, an ink font, and means for automatically intermittently driving the inking pad from the font to the marking wheels and return.

In witness whereof, I, have hereunto set my hand and seal at Peru, Indiana, this 19th day of September, A. D. one thousand nine hundred and eight.

GEORGE M. DIEHL. [L. s.]
